United States Patent Office

Des. 192,537
Patented Apr. 3, 1962

192,537

BOTTLE

Arthur Hewitt, Hollywood, Calif., assignor to Schenley
Industries, Inc., New York, N.Y., a corporation of Delaware

Filed May 31, 1960, Ser. No. 60,799

Term of patent 14 years

(Cl. D58—6)

FIGURE 2 is a side view of the front half of said bottle. The other half is similar but plain.

The essential feature of my design resides in the portions shown in full lines.

I claim:

The ornamental design for a bottle, as shown and described.
